UNITED STATES PATENT OFFICE.

WILLIAM C. BAXTER, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MECHANICAL MOVEMENT.

1,292,565.

Specification of Letters Patent. Patented Jan. 28, 1919.

Original application filed February 24, 1913, Serial No. 750,326. Divided and this application filed November 27, 1915. Serial No. 63,853.

To all whom it may concern:

Be it known that I, WILLIAM C. BAXTER, a citizen of the United States, residing at Beverly, in the county of Essex and State of Massachusetts, have invented certain new and useful Improvements in Mechanical Movements; and I do hereby declare the following to be a full, clear, and exact description of the invention, such as will enable others skilled in the art to which it appertains to make and use the same.

The present invention relates to mechanical movements and more particularly to mechanism for converting rotary into reciprocatory motion, or vice versa.

The object of the present invention is to provide an improved mechanism for converting rotary into reciprocatory motion which is adjustable during the operation of the machine to vary the extent of the reciprocatory motion, and which imparts a plurality of reciprocations to the driven member for each complete rotation of the driving shaft.

With this object in view a feature of the invention contemplates the provision of a pair of rotary members positioned eccentric to one another, means for rotating one of the members, and a floating member interposed between the two first mentioned members and operatively connected with both members to lock all of the members against relative rotation while permitting a relative reciprocatory movement of the floating member.

A further feature of the invention consists in the combination of a driving member, means for rotating the driving member, a controlling member positioned eccentric to the driving member, a floating member interposed between the two first mentioned members and having tongue and groove connections disposed at right angles between opposite faces of the floating member and the driving and controlling members.

Still further features of the invention consist in certain novel features of construction, combinations and arrangements of parts hereinafter described and claimed, the advantages of which will be obvious to those skilled in the art from the following description.

In the accompanying drawings illustrating the preferred form of the invention;

Figure 1 is a plan view partly in section of the improved mechanism; Fig. 2 is a side elevation of the mechanism shown in Fig. 1; Fig. 3 is a detail illustrating an elevation of the floating disk showing the relative location of the opposite spline connections; Fig. 4 is a detail showing a section in elevation of the floating disk with the coöperating disks indicated in dotted outline; Fig. 5 is a detail showing a side elevation of the several disks linked together; Fig. 6 is a detail showing a cross section of the disks in the relative positions illustrated in Fig. 5; Fig. 7 is a plan view illustrating the embodiment of the improved mechanism in a sole leveling machine having a pair of leveling rolls; and Figs. 8 to 11, inclusive, are details illustrating the position of the floating disk during each quarter turn of the driving shaft. In the illustrated embodiment of the invention shown in the drawings this mechanism comprises a pair of coöperating rotary members which are supported eccentric to one another, means for rotating one of the members, and a floating member interposed between the two first mentioned members and operatively connected with both members to lock all of the members against relative rotation while permitting a relative reciprocatory movement of the floating member. In the simplest and most efficient form of the invention which has yet been devised a driving disk is secured to a driving shaft and a second or controlling disk, as it may be termed, is positioned eccentric to the driving disk and is adjustable relative thereto. A floating disk is interposed between the two first mentioned disks and is connected with both disks through tongue and groove connections disposed at right angles and connecting opposite faces of the floating disk with the driving and controlling disks, respectively. With this construction the extent of vibratory movement imparted to the floating disk is determined by the eccentricity of the controlling disk with relation to the driving disk, the rotation of the driving disk causing the floating disk to rotate and to reciprocate between the axes of the driving and controlling disks. In the mechanism illustrated in the drawings a driving shaft 1 is provided with a driving disk 3 secured thereto. A control-

ling disk 5 has an extended hub 6 journaled in bearings formed in a head 7 and provided with an enlarged bore 8 to permit an adjustment of the disk relative to the driving shaft 1. The disks 3 and 5 are spaced from one another and a floating disk 10 is interposed between the two disks and is locked against rotation relative to the disks through tongue and groove connections indicated respectively at 12 and 13. The driving connections with opposite faces of the disk 10 extend at right angles and when the driving disk is rotated impart a reciprocatory motion to the floating disk 10 through the joint action of the driving disk 3 and controlling disk 5. The motion imparted to the controlling disk causes two complete reciprocations of the disk and driven member connected therewith for each rotation of the shaft, as will be obvious from an inspection of Figs. 8 to 11, inclusive. Referring to these figures it will be noted that during the first quarter turn of the driving shaft the tongue and groove connection 12 between the disks 3 and 10 is turned from a horizontal into a vertical position, causing a movement of the floating disk to its most advanced position, during the second quarter turn the connection 13 between the disks 3 and 10 is moved into a vertical position, retracting the floating disk to its initial position and during the third and fourth quarter turns of the shaft the preceding cycle of operations is repeated. It will be seen from the above that the extent of the reciprocatory movement imparted to the floating disk is equal to the distance between the axes of the disks 3, 5, and that by varying the spaced relation of the axes a predetermined amount the extent of the reciprocatory movement may be accordingly varied.

The illustrated embodiment of the invention is conveniently shown in connection with the machine disclosed in the U. S. patent to Baxter No. 1,208,895, dated December 19, 1916, and from which the present application is divided. This machine has twin operating tools indicated at 15, each of which is connected with its respective vibrating mechanism through a yoke 16, connecting rod 17, slide 18, and a pitman 19 having a strap 20 received in a peripheral groove 21 formed in the floating disk 10. It will be noted from an inspection of Fig. 7 that both of the driven members are reciprocated from a common drive shaft 1 and in order to simultaneously adjust the extent of movement of both of the driven members the head 7 is provided with oppositely disposed bearings which receive two controlling disks 5. The head 7 is slidably supported in guideways 23 formed in the frame and is provided with an upstanding projection 22 which threadedly receives the end of an adjusting rod 24. The adjusting rod 24 is

journaled and held against lengthwise movement in a bearing 25 and at its forward end is provided with a hand wheel 26 conveniently accessible to the operator. In order to limit the extent of movement of the head 7 the adjusting rod 24 is provided with a pair of collars 28 arranged upon opposite sides of the member 22 to limit the movement of the adjusting rod with relation to the member.

While it is preferred to employ the specific construction and arrangement of parts shown and described, it will be understood that this construction and arrangement is not essential except so far as specified in the claims, and may be changed or modified without departing from the broader features of the invention.

The invention having been described, what is claimed is:

1. A mechanism for converting rotary into reciprocatory motion, comprising a pair of rotary members positioned eccentric to one another, means for rotating one of the members, a floating member interposed between the two first mentioned members and operatively connected with both members to lock all of the members against relative rotation while permitting a relative reciprocatory movement of the floating member, a driven member, and connections for reciprocating the driven member from the floating member.

2. A mechanism for converting rotary into reciprocatory motion, comprising a pair of rotary members positioned eccentric to one another, means for rotating one of the members, means for varying the eccentricity of the two members, a floating member interposed between the two first mentioned members and operatively connected with both members to lock all of the members against relative rotation while permitting a relative reciprocatory movement of the floating member, a driven member, and connections for reciprocating the driven member from the floating member.

3. A mechanism for converting rotary into reciprocatory motion, comprising a pair of rotary disks positioned eccentric to one another, means for rotating one of the disks, a floating disk interposed between the two first mentioned disks and having tongue and groove connections disposed at right angles and connecting opposite faces of the floating disk with the driving and controlling disks, respectively, a driven member, and connections for reciprocating the driven member from the floating disk.

4. A mechanism for converting rotary into reciprocatory motion, comprising a pair of rotary disks positioned eccentric to one another, means for rotating one of the disks, a floating disk interposed between the two first mentioned disks and having tongue and

groove connections disposed at right angles and connecting opposite faces of the floating disk with the driving and controlling disks, respectively, a driven member, and connections between the floating disk and driven member.

5. A mechanism for converting rotary into reciprocatory motion, comprising a driving member, means for rotating the driving member, a controlling member positioned eccentric to the driving member, means for adjusting the controlling member to vary the eccentricity of the controlling member with relation to the driving member, a floating member interposed between the two first mentioned members, connections between the opposite faces of the floating member and the driving and controlling members to lock all of the members against relative rotation while permitting relative reciprocatory movements of the floating member, a driven member, and connections between the floating member and driven member to reciprocate the driven member.

25. 6. A mechanism for converting rotary into reciprocatory motion, comprising a driving shaft, a driving disk secured to the shaft, a head adjustable transversely of the shaft,

a controlling disk journaled in the head, and a floating disk interposed between the driving and controlling disks and having tongue and groove driving connections with the disks.

7. A mechanism for converting rotary into reciprocatory motion, comprising a driving disk, a head adjustable transversely of the driving disk, an adjusting rod threadedly connected with the head, a controlling disk journaled in the head, and a floating disk interposed between the controlling and driving disks and having tongue and groove driving connections with both disks.

8. A mechanism for converting rotary into reciprocatory motion, comprising a driving disk, a controlling disk supported eccentric to the driving disk, a floating disk interposed between the controlling and driving disks and operatively connected with both disks to lock all of the disks against relative rotation while permitting a relative reciprocatory movement of the floating disk, a driven member, and a strap surrounding the periphery of the floating disk and connected with the driven member.

WILLIAM C. BAXTER.
